(75) Inventors: **Robert Fraser Wilson**, Vancouver (CA); **Edmond Kwok Ho Fung**, Lexington, MA (US)

* cited by examiner

(73) Assignee: **PerComm, Inc.**, Vancouver (CA)

Primary Examiner—Freda Nunn

(**) Term: **14 Years**

(74) *Attorney, Agent, or Firm*—Oyen Wiggs Green & Mutala

(21) Appl. No.: **29/172,191**

(57) **CLAIM**

(22) Filed: **Dec. 9, 2002**

The ornamental design for a wireless handheld communication device with joystick manipulator, as shown and described.

(51) **LOC (7) Cl.** **14-02**

DESCRIPTION

(52) **U.S. Cl.** **D14/341**

(58) **Field of Search** D14/341-346,
D14/191, 397, 412; D18/1, 2, 7; 235/145 A,
145 R; 341/22, 23; 345/156, 168, 169,
172, 173, 87; 361/680-686
